UNITED STATES PATENT OFFICE.

PETER S. KEENAN, OF KEMMERER, WYOMING.

MINER'S LAMP.

No. 839,002.

Specification of Letters Patent.

Patented Dec. 18, 1906.

Application filed July 28, 1906. Serial No. 328,238.

To all whom it may concern:

Be it known that I, PETER S. KEENAN, a citizen of the United States, residing at Kemmerer, in the county of Uinta and State of Wyoming, have invented new and useful Improvements in Miners' Lamps, of which the following is a specification.

This invention relates to improvements in miners' lamps; and it consists of the novel features of construction and combination of parts hereinafter fully described and claimed.

The object of the invention is to provide a lamp having improved supporting and wick-picking means and an improved construction of wick-tube having means for securing a central draft to promote combustion and insure the production of a clearer light.

In the accompanying drawings, Figure 1 is a side elevation of a miner's lamp embodying my invention. Fig. 2 is a central vertical front to rear section through the same. Fig. 3 is a rear elevation. Fig. 4 is a top plan view with the cover thrown open. Fig. 5 is a detail view of the combined supporting device and pick.

Referring to the drawings, the numeral 1 designates the body or font of the lamp, which may be closed at top by any suitable form of cover 2. Arranged at the front of the body is a wick-tube 3, provided with an air-passage 4, extending axially or centrally through and communicating at its lower end with an inlet 5, formed in the bottom of the font. The wick-tube communicates at its lower end with the interior of the font, and the wick in practice is designed to be arranged therein about the passage 4, through which latter a current of air is supplied at the point of combustion to permit the wick to burn freely and to produce a clear and bright light.

Preferably the wick-tube and passage 4 are formed of a single piece of sheet metal closed at rear by a seam 5, the metal being folded inwardly at the front and shaped to form the tube 4 and then bent to provide flattened portions 6, closing the wick-tube at the point of folding and supporting the air-tube therein. The portions 6 may be secured together by the use of solder or any other suitable fastening means.

Arranged upon the rear of the font is a holder comprising a pair of spring-strips 7, permanently fastened at their upper ends to

the upper end of the font and having their lower ends bent or curved outwardly, as at 8, to provide flaring entrance and exit passages between the same and font. The strips are spaced apart for the reception between the same of the combined supporting device 6 and pick hereinafter described, and adjacent their upper ends are outwardly offset to form keeper-loops 9.

The combined supporting device and pick comprises a stem 10, formed at its upper end into a hook 11 for supporting the lamp from the miner's cap, and having its lower end pointed, as at 12, to provide a pick, whereby the wick may be picked or loosened and adjusted in the wick-tube when occasion requires, thus obviating the necessity of employing the primitive methods of accomplishing this result heretofore employed in lamps unprovided with wick-raising devices. The stem 10 is formed or provided with laterally-extending pins or lugs 13, adapted to engage the keeper-loops 9, whereby the supporting device and pick may be detachably secured to the lamp.

It will be understood that in detaching the supporting device the latter is forced downwardly, thus causing the pins 13 to press the spring-strip 7 outwardly. When said pins arrive at the flared portions 8, the supporting device may be readily removed in an obvious manner. In applying the supporting device the latter is placed on a line between the strips 7 with the pins 13 in the spaces between the lamp-body and bent ends 8 of the strip, and the supporting device is then drawn upwardly by means of the hook 11, the pins 13 riding upward between the strips and lamp-body until they snap into the keepers 9, when the supporting device will be securely held in position.

It is thought that the structural features and advantages of the invention will be fully understood from the foregoing description and the advantages fully appreciated by those familiar with this class of devices.

Having thus described the invention, what is claimed as new is—

1. A miner's lamp comprising a font provided with a wick-tube having an air-tube disposed therein for securing a central draft, said tubes being formed from a single strip of metal.

2. A miner's lamp comprising a font pro-

vided with a wick-tube having an air-tube disposed therein and communicating with an air-passage in the bottom of the font, said tubes being formed from a single piece of sheet metal, the metal being folded inwardly to produce the air-tube.

3. A miner's lamp having a combined wick-tube and air-passage, the same being formed from a single piece of sheet metal joined at one side and folded inwardly from the opposite side to produce the air-passage, the metal also being folded to form a closed union between the wick-tube and air-passage.

4. A miner's lamp having a holder at the 15 rear thereof, comprising a pair of spring-strips secured at their upper ends and free from connection at their lower ends, said strips being spaced and bent to form keepers and a supporting device comprising a stem 20 having lugs to ride between the lamp-body and strips and engage said keepers.

In testimony whereof I affix my signature in presence of two witnesses.

PETER S. KEENAN.
